CLAIM

The ornamental design for a front face of a vehicle wheel, as shown and described.

DESCRIPTION

This application is related to co-pending application Ser. No. 29/151,713, of the inventor, filed Dec. 11, 2001 and entitled “front face of a vehicle wheel.”

FIG. 1 is a front view of a first embodiment of a front face of a vehicle wheel according to my novel design; FIG. 2 is a perspective view of the first embodiment of the front face of a vehicle wheel according to my novel design; FIG. 3 is a front view of a second embodiment of the front face of a vehicle wheel according to my novel design; and, FIG. 4 is a perspective view of the second embodiment of the front face of a vehicle wheel according to my novel design.

The dash lines included depict environment and are not part of the claimed design.

1 Claim, 2 Drawing Sheets

FIG. 3

FIG. 4
